UNITED STATES PATENT OFFICE.

JOHN HENRY MILNES, OF HUDDERSFIELD, ENGLAND.

MACHINE OR APPARATUS FOR DYEING, WASHING, AND THE LIKE.

1,230,198.

Specification of Letters Patent. Patented June 19, 1917.

Application filed December 7, 1916. Serial No. 135,696.

To all whom it may concern:

Be it known that I, JOHN HENRY MILNES, a subject of the King of Great Britain and Ireland, residing at Huddersfield, in the 5 county of York, England, have invented a new and useful Improvement in Machines or Apparatus for Dyeing, Washing, and the like, of which the following is a specification.

10 This invention relates to certain improvements in machines or apparatus for the dyeing, washing, or other liquid treatment of wool, rags, shoddy, and the like.

In these processes an apparatus has ordinarily been employed consisting of a vat or receptacle divided into upper and lower compartments by means of a perforated plate, and having a central circulating tube leading from the lower compartment 20 and extending upwardly through the upper compartment to a point above the level of the liquid within the vat, the circulation being set up and maintained (up the central tube and down through the material and 25 perforated plate) by means of steam or compressed air introduced into the lower compartment by way of a supply main and perforated coil. In this known type of apparatus it has also been proposed to introduce 30 the coloring matter into the vat by way of a funnel or like receptacle having a branch pipe connection to the said steam or compressed air supply main. It has also been proposed in another type of apparatus to lift 35 and agitate the material within the upper compartment of the vat by means of compressed air introduced into the lower compartment by way of a supply main and perforated coil and from thence passed upward 40 through the perforated plate and through the material.

My present invention relates to the aforesaid type of apparatus having the upper and lower compartments, the intermediate perforated plate, the central circulating tube, and the steam supply main, and my improvement consists mainly in the combination therewith of an auxiliary supply pipe designed to introduce an auxiliary supply of 45 air into the lower compartment and to pass same upward through the perforated plate for the purpose of lifting and agitating the material, said auxiliary air supply being controlled by a steam-operated air injector 50 having a branch connection from the steam supply main, and said auxiliary air supply

being utilized either separately or concurrently with the ordinary steam supply so as to obtain either a single or a double circulation. A further feature of my invention lies 60 in the introduction of the coloring matter by way of a branch connection to the auxiliary air supply pipe.

The accompanying drawing shows an elevation in section of a dye vat of the type 65 referred to and having my improvements applied.

D is the ordinary vat, having upper compartment E, lower compartment F, intermediate perforated plate G, central circulation tube I, and steam supply main K with valve L.

According to my invention the steam supply main K is provided with a branch pipe M having valve J, this branch steam pipe M 75 being operatively connected to an air injector H fitted in an auxiliary air supply pipe A, which is carried down through the vat into the lower compartment F and terminates in a perforated coil B around the 80 bottom of the vat. The auxiliary air supply pipe A is also fitted with a branch pipe N having a valve O and an ordinary inlet funnel C for the dye liquid or coloring matter.

When the apparatus is in use the ordinary heating circulation is effected by steam introduced by way of the steam supply main K. When lifting or agitation of the material is considered desirable, the branch steam valve J is opened to the injector H and air is forced down the auxiliary air supply pipe A to the perforated coil B, from whence it is forced through the perforated plate G and up through the material, agitating and lifting the material throughout without the necessity for stanging or poling. The ordinary steam supply through the main K for the heating circulation, and the auxiliary air supply through the branch A for the lifting circulation, may be utilized either separately or concurrently as desired. The dye liquid or coloring matter is introduced by way of the inlet funnel C and branch pipe N, and is forced down the pipe A and delivered 100 along with the auxiliary air supply from the perforated coil B, thus insuring effective distribution and thorough mixing with the liquor within the vat.

I claim:

1. In dyeing apparatus and the like of the type having the ordinary upper and

lower compartments, intermediate perforated plate, central circulating tube, and steam supply main, the employment in combination therewith of an auxiliary pipe designed to introduce an auxiliary supply of air into the lower compartment and to pass same upward through the perforated plate for the purpose of lifting the material, said auxiliary air supply being controlled by a steam operated air injector having a branch connection from the steam supply main, and said auxiliary air supply and ordinary steam supply being utilizable either separately or concurrently, substantially as herein set forth.

2. In dyeing apparatus and the like of the type having the ordinary upper and lower compartments, intermediate perforated plate, central circulating tube, and steam

supply main, the employment in combination therewith of an auxiliary pipe designed to introduce an auxiliary supply of air into the lower compartment and to pass same upward through the perforated plate for the purpose of lifting the material, said auxiliary air supply being controlled by a steam operated air injector having a branch connection from the steam supply main, and said auxiliary air supply and ordinary steam supply being utilizable either separately or concurrently, and a dye liquor inlet funnel and branch pipe applied to the auxiliary air supply pipe.

JOHN HENRY MILNES.
